[57] CLAIM

The ornamental design for a hand fan, as shown.

DESCRIPTION

FIG. 1 is a perspective view, as seen from a front side, of a hand fan showing my new design;

FIG. 2 is a rear elevational view thereof;

FIG. 3 is a right side view thereof, the left side being identical;

FIG. 4 is a top plan view thereof; and,

FIG. 5 is a bottom plan view thereof.
